US0D1113296S

(12) United States Design Patent (10) Patent No.: US D1,113,296 S
 Della Pietra (45) Date of Patent:  Feb. 17, 2026

(54) COFFEE MACHINE EXCEPT FOR HOUSEHOLD PURPOSES

(71) Applicant: LA MARZOCCO S.R.L., Scarperia (IT)

(72) Inventor: Stefano Della Pietra, Scarperia e San Piero (IT)

(73) Assignee: LA MARZOCCO S.R.L., Scarperia (IT)

() Term: 15 Years

(21) Appl. No.: 29/944,994

(22) Filed: May 31, 2024

Related U.S. Application Data

(62) Division of application No. 35/516,815, filed on Nov. 8, 2022 (U.S. filing date under 35 U.S.C. 384), and having an international filing date of Nov. 8, 2022, now Pat. No. Des. 1,047,561.
